METAL BENDING PRESS

Application filed December 13, 1930. Serial No. 502,080.

This invention relates to metal bending presses wherein a ram cooperates with a die to bend an edge or edges of a metal plate therebetween in two directions to form the 5 edge or edges into substantially U-shape, and while we have particularly developed the apparatus herein disclosed for use in constructing automobile window panels, it is clear that the same is adapted to other like uses within 10 the scope of the invention. The bending of metal sheets by acting thereon in two directions to form U-shaped edges of this nature has heretofore commonly required the use of two or more mechanisms and two or more distinct operations, and one of the objects of our 15 invention is to provide a single mechanism which will operate thereon in two directions and thereby form these edges into U-shape in a single pressing operation.

20 In accordance with our invention, a rectangular window panel frame having edge portions thereof extending into the opening in the frame is supported on a die, the inner edges of which are undercut. A ram cooperates with the die and is adapted to first engage said edge portions to bend them downwardly and thereafter move relatively outward in a manner forcing the downwardly bent edge portions beneath said undercut die 25 edges, the two direction movement of the bending elements thereby forming the blank edges into U shape about the undercut die edges. Upon upward movement of the ram, reverse movement is given to the bending elements, whereby they freely withdraw from the die. The invention furthermore includes means for so movably mounting the undercut portions of the die that the same may be moved to a position permitting removal of the finished work and, in accordance with the preferred form of our invention, these portions are automatically moved to this position upon upward movement of the ram. Another object of our invention is to provide a mechanism 35 of this nature for the purpose stated.

In the accompanying drawings, we have illustrated certain specific embodiments of our invention but it will be understood that the invention can be otherwise embodied and that 40 the drawings are not to be construed as de-

fining or limiting the scope of the invention, the claims appended hereto being relied upon for that purpose.

Referring to the figures of the drawings, Fig. 1 is a side elevation, partially in section, of a bending press embodying our invention;

Fig. 2 is a fragmentary sectional view thereof showing one step in the operation;

Fig. 3 is a like view showing a further step in the operation;

Fig. 4 is a plan sectional view taken on line 4—4 of Fig. 1;

Fig. 5 is a perspective view of a work piece after being treated by our press;

Fig. 6 is a fragmentary view of one of the bending elements;

Fig. 7 is a perspective view of a detail; and

Fig. 8 is a fragmentary sectional view showing how the finished work is released from the die.

We have in the accompanying drawings illustrated the application of our invention to certain steps in the formation of automobile window panels. Such a panel frame 10 comprises a sheet metal plate having a relatively large opening 12 therein. The work piece is shown in Fig. 1 in the shape in which it is presented to the mechanism of our invention, it having been previously formed to this shape by other mechanism. It will be noted that the sheet has been depressed entirely therearound at 14 and has downwardly bent edge portions 16 and connected edge portions 18 extending therefrom into the opening 12. The function of the mechanism comprising our invention is to bend the inwardly extending portions 18 from the position shown in Fig. 1 to the position shown in Figs. 3, 5 and 8 in one operation or stroke of the machine. We will now proceed to describe this mechanism as illustrated in the accompanying drawings.

Our invention, as shown in Fig. 1, comprises a die 20 and a cooperating ram 22. Surrounding an opening 24 in the die are four work holding elements 26 and 28, each pivoted to the die at 30 and normally resting firmly thereon, as in Fig. 1. The elements 26 are relatively long and oppositely disposed

and the elements 28 are relatively short and oppositely disposed at the ends of the elements 26, the four elements being of a size and their top surfaces so shaped as to receive and support the work piece 10 in close cooperation thereon and with the portion 18 extending inwardly of the openings 12 and 24. The inner portions of the elements 26 and 28 are undercut at 32 to provide anvils 34 around which the work piece is to be bent.

The ram 22 has extending downwardly therefrom a plurality of bolts, three such bolts 36 being over each element 26 and two bolts 37 being over each element 28. On the lower end of each bolt is a relatively long locating stud 38 adapted to engage in cooperating holes 40 in the die. Each bolt also has an intermediate guide portion 42 and a collar 44 at the junction thereof with the stud. Supported on the three bolts 36 adjacent to each side element 26 is a relatively long bending element 46 and likewise supported on each pair of bolts 37 adjacent to each element 28 is a relatively short bending element 47, each of these elements having a stop portion 48 engaging the collars 44 and an inclined surface 50 engaging like inclined surfaces on the collars. The portions 42 of the bolts extend through elongated slots 51 in the elements 46 and 47. A plate 52, guided on the bolt portion 42, rests on the elements 46 and in conjunction with springs 54 between the plate and ram normally keeps the elements in a position wherein the shoulders 48 rest against the collars 44, as in Fig. 1. This plate 52 has an elongated central portion 53 integral therewith and normally extending downwardly to a position slightly below the members 46 and 47 when the ram is in its raised position.

Cooperating with inclined surfaces on the elements 46 and 47, and parallel with the surfaces 50, are four blocks 56 secured to the ram by bolts 60, each block having two inclined surfaces 61 and 62 respectively engaging cooperating inclined surfaces 63 and 64 on the elements 46 and 47. These blocks are slidably supported in openings in the plate 52. Work clamping elements 66 connected to and operated by the ram in any convenient manner are provided for holding the work against the die during the operations thereon.

It will be noted that the elements 26 and 28 are illustrated as pivotally mounted whereby they can be moved from the position shown in Fig. 3 to the position shown in Fig. 8, for the purpose of permitting removal of the finished work therefrom, and in accordance with the mechanism which I will now describe these elements are preferably automatically so moved for this purpose. Extending rearwardly from each element 26 and 28 is a stud 68 with which cooperates a lever 70 pivoted on a bracket 72 secured to

the die. A spring 74 normally keeps the lever engaged against its lug, as illustrated. Carried by each work clamping element 66 is a downwardly extending bar 76 having a hook 78 on its lower end and this hook is so located that it engages the outer end of its lever 70 on both the upward and downward strokes of the ram. The hook is beveled at 80 whereby it rides over the lever on the downward stroke. On each upward stroke of the ram, the hooks engage the levers and cause the elements 26 and 28 to pivot upwardly to the work releasing position shown in Fig. 8.

The operation of the device is substantially as follows. When the ram 22 is in raised position, the work piece 10 is placed thereon, as shown in Fig. 1, wherein the ram is illustrated as somewhat moved downwardly from its uppermost position, the work readily fitting onto the elements 26 and 28. As the ram approaches the die, the studs 38 engage within the holes 40 in the die and the elements 66 engage and clamp the work in place. Continued downward movement of the ram engages the elements 46 and 47 with the work portions 18 and bend them downwardly to the position shown in Fig. 2. When the member 53 engages against the die, continued downward movement of the ram compresses the springs 54 and forces the blocks 56 against the members 46 and 47, and the engaging inclined faces thereof force the members outwardly in a manner bending the work portions 18 to the position shown in Fig. 3. It will be noted that the member 53 normally extends to a position slightly below the elements 46 and 47, whereby this member takes the thrust of the compression of springs 54 and thereby prevents binding of the bending elements between the plate 52 and the die, the elements being, therefore, free to move outwardly under the action of the blocks 56.

When the ram rises, the springs 54 expand and the engagement of the collars 44 with the inclined surfaces 50 automatically moves the elements 46 and 47 inwardly to their initial position. Upon continued upward movement of the ram, the hooks 78 engage the levers 70 and tip the members 26 and 28 to the position of Fig. 8, thus permitting the work to be removed. The hooks continue on to a position above that shown in Fig. 8 and the members fall back to their normal position on the die, it being understood that the operator removes the work as the elements reach a position approaching that shown in Fig. 8.

Having thus described our invention, what we claim as new and desire to secure by Letters Patent is:

1. In a bending press, a die member having an opening therein and a plurality of work-holding elements adjacent to the edge of the opening, said elements having undercut portions extending inwardly of the open-

- ing, a ram cooperating with the die, means carried by the ram for engaging and bending downwardly portions of a work piece extending over said undercut portions and into the opening, and cooperating means for bending the lower ends of said downwardly bent portions laterally beneath said undercut portions of the elements.
2. In a bending press, a die member having an opening therein and a plurality of work-holding elements adjacent to the edge of and entirely surrounding the opening, said elements having undercut portions extending inwardly of the opening, a ram cooperating with the die, means carried by the ram for engaging and bending downwardly portions of a work piece extending over said undercut portions and into the opening, cooperating means for bending the lower ends of said downwardly bent portions laterally beneath said undercut portions of the elements, and means so mounting the elements that they may be moved to a work-releasing position.
3. In a bending press, a die member having an opening therein and a plurality of work-holding elements adjacent to the edge of the opening, said elements having undercut portions extending inwardly of the opening, a ram cooperating with the die, means carried by the ram for engaging and bending downwardly portions of a work piece extending over said undercut portions and into the opening, cooperating means for bending the lower ends of said downwardly bent portions laterally beneath said undercut portions of the elements, and means so pivotally mounting the elements that their undercut portions can be pivoted upwardly to release the finished work.
4. In a bending press, a die member having an opening therein and a plurality of work-holding elements adjacent to the edge of the opening, said elements having undercut portions extending inwardly of the opening, a ram cooperating with the die, means carried by the ram for engaging and bending downwardly portions of a work piece extending over said undercut portions and into the opening, cooperating means for bending the lower ends of said downwardly bent portions laterally beneath said undercut portions of the elements, and means automatically operative synchronously with the ram for moving the elements to work-releasing position.
5. In a bending press, a die member having an opening therein and a plurality of work-holding elements adjacent to the edge of the opening, said elements having undercut portions extending inwardly of the opening, a ram cooperating with the die, means carried by the ram for engaging and bending downwardly portions of a work piece extending over said undercut portions and into the opening, cooperating means for bending the lower ends of said downwardly bent portions laterally beneath said undercut portions of the elements, and means pivotally mounting the elements, and means whereby upon upward movement of the ram the elements are automatically pivoted upward to release the work.
6. In a bending press, a die member having an opening therein and a plurality of work-holding elements adjacent to the edge of the opening, said elements having undercut portions extending inwardly of the opening, a ram cooperating with the die, means carried by the ram for engaging and bending downwardly portions of a work piece extending over said undercut portions and into the opening, and cooperating means carried by the ram for causing the first-named means to move outwardly and force said downwardly bent portions of the work piece beneath the undercut portions of said elements.
7. In a bending press, a die member having an opening therein and a plurality of work-holding elements adjacent to the edge of the opening, said elements having undercut portions extending inwardly of the opening, a ram cooperating with the die, means carried by the ram for engaging and bending downwardly portions of a work piece extending over said undercut portions and into the opening, cooperating means carried by the ram for causing the first-named means to move outwardly and force said downwardly bent portions of the work piece beneath the undercut portions of said elements, means for withdrawing the first-named means inwardly upon upward movement of the ram, and means so adjustably mounting said elements that they can be moved to a position releasing the finished work from the die.
8. In a press for shaping the inner edges of a ring-like plate, a die member having an opening therein and a plurality of work-holding elements adjacent to the edge of and entirely surrounding the opening, said elements having undercut portions extending inwardly of the opening, a ram cooperating with the die, means carried by the ram for engaging and bending downwardly portions of a work piece extending over said undercut portions and into the opening, and cooperating means carried by the ram for bending the lower ends of said downwardly bent portions laterally beneath said undercut portions of the elements when the ram approaches its extreme downward position.
9. In a metal bending press, a die, a ram cooperating therewith, a plate carried by the ram, a plurality of studs supporting the plate on the ram and permitting a limited movement thereof toward the die, resilient means normally forcing the plate to said limit, a bending element engaged by the plate, and means carried by the studs and ram for engaging the work.

gaging inclined surfaces at opposite sides of the element and acting thereon to move the element laterally when engaging the die and returning the element to normal position

5 when the ram is raised.

10. In a metal bending press, a die, a ram thereabove and cooperating therewith, a plate, a plurality of studs depending from the ram and supporting the plate on and be-

10 beneath the ram and permitting a limited movement thereof toward and from the die relative to the ram, a bending element carried by the studs beneath and engaged by the plate, means carried by the ram and engag-

15 ing an inclined surface on the element for moving the element laterally when the ram engages and moves toward the die, and means including resilient means for returning the element to normal position when the ram is

20 raised.

11. In a metal bending press, a die, a ram cooperating therewith, a bending element, a plurality of studs supporting the element, locating pins carried by the studs and adapted

25 to engage corresponding holes in the die, means carried by the ram and engaging an inclined surface on the element for moving the element laterally when engaging the die, and means including resilient means between

30 the ram and element and inclined engaging surfaces between the studs and element for returning the element to normal position when the ram is raised.

12. In a metal bending press, a die, a ram

35 cooperating therewith, a plurality of relatively angular bending elements in end to end relation, a plurality of studs supporting each element on the ram, locating pins carried by the studs and adapted to engage correspond-

40 ing holes in the die, means carried by the ram and engaging inclined surfaces on the elements for moving the elements laterally upon downward movement of the ram and relative movement between said means and surfaces,

45 and means for moving the elements laterally in the opposite direction upon upward movement of the ram.

13. In a bending press, a die member having an opening therein and a plurality of 50 work-holding elements adjacent to the edge of the opening, said elements having undercut portions extending inwardly of the opening, a ram cooperating with the die, means carried by the ram for engaging and bend-

55 ing downwardly portions of a work piece extending over said undercut portions and into the opening, cooperating means for bending the lower ends of said downwardly bent portions laterally beneath said undercut por-

60 tions of the elements, and means preventing frictional engagement of the bending means between the ram and die during said lateral bending operation.

14. In a metal bending press, a die, a ram 65 cooperating therewith, a plate carried by the

ram, a plurality of studs supporting the plate on the ram and permitting a limited movement thereof toward the die, a bending element carried by the studs and engaged by the plate, means carried by the ram and engaging an inclined surface on the element for moving the element laterally when engaging the die, means including resilient means for returning the element to normal position when the ram is raised, and means preventing binding of the bending element between the plate and die during said lateral movement of the element.

15. In a metal bending press, a die, a ram cooperating therewith, a plate carried by the ram, a plurality of studs supporting the plate on the ram and permitting a limited movement thereof toward the die, a bending element carried by the studs and engaged by the plate, resilient means normally moving the plate toward the die, a block carried by the ram and guided by engagement with the plate, the block and element having cooperating inclined surfaces for moving the element laterally upon relative movement of the block and element, means providing an abutment between the die and plate for preventing their frictional engagement with the element during its said lateral movement, and cooperating means for returning the element laterally to its initial position upon upward movement of the ram.

In testimony whereof we affix our signatures.

LEE F. SICKLER.
PETER J. LINSTROM.
